VARIABLE PITCH PROPELLER

Filed Dec. 30, 1943

UNITED STATES PATENT OFFICE

2,557,127

VARIABLE PITCH PROPELLER

Herbert L. Magill, Chicago, Ill.

Application December 30, 1943, Serial No. 516,258

7 Claims. (Cl. 170—135.4)

1

This invention relates to variable pitch propellers operating in fluid mediums, and the principal object of the invention is to provide automatic pitch controlling mechanism that continuously adjusts the speed and pitch of the propeller to values which effectively balance the power input to the propeller.

Other and further objects and advantages of the invention will appear from the following description, taken in connection with the accompanying drawings in which

Fig. 1 is a vertical sectional view, shown more or less diagrammatically, showing a preferred embodiment of my invention, with parts of the view being broken away for clarification.

Fig. 2 is a section of a detail construction of the friction device shown in Fig. 1.

The propeller 15 is shown as an aircraft propeller, but could be a propeller for use in any fluid medium. It is propelled in any suitable manner, as for example, by reaction jets, located at or near the tips of the propeller blades on the trailing edges thereof, and through which the exhaust from a gas pressure generator 19 is discharged. The propeller blades are so mounted that their pitch is automatically or manually changed as desired, as the plane varies in altitudes. At low altitudes the plane is propelled principally by the forced rotation of the blades 15 by the reaction jets, but at high altitudes the plane is propelled by the reaction jets on the propeller blades, augmented, if necessary, by additional reaction jets.

Mechanism for varying the pitch of propeller blades

Attached to and extending forwardly from the pressure generator is a mounting or housing 212, within which is rotatably mounted the propeller shaft 213. Suitable anti-friction bearings 214, 215, are provided for this shaft within the housing 212. The propeller 15 is attached to the hub 224 in such a manner that the propeller blades may be varied in pitch, as will now be described.

Attached to the forward end of the propeller shaft 213 is a hub 224, within which the inner ends of the propeller blades 220 are rotatably mounted, as by means of anti-friction bearings 225. The inner end of each blade or vane 220 has a bevel gear 226 rigidly mounted thereon, which in turn meshes with a corresponding bevel gear 227 rigidly mounted on a shaft 223. It will thus be seen that when the shaft 223 is rotated relatively to the propeller shaft 213 the propeller

2

blades 220 will be rotated about their longitudinal axes, due to the meshing of the gear 227 with the gears 226 on the inner ends of the propeller blades.

5 Each of the propeller blades is provided with a conduit 222, which extends longitudinally of the blades and have their inner ends enlarged, as at 222^a, and through which the exploded gases from the pressure generator 19 are conducted to the reaction jet nozzles located on the rear or trailing edges of the propeller blades, as previously described.

The propeller shaft 213 is hollow, and the tubular conduit 178 extends axially therethrough.

10 At its rear end the tubular conduit 178 is rigidly connected to the propeller shaft by a bracket or supporting member 216.

15 The forward end of the tubular conduit 178 is provided with branch conduits, one for each propeller blade. Where the propeller has but two blades, as shown in Fig. 1, the conduit 178 is bifurcated, or terminates in a T-shaped hollow member 218, the arms 219 of which extend laterally into the enlarged ends of conduits 221 and 222, extending lengthwise of the propeller blades 220, and through which the exploded gases from the pressure generator 19 are conducted to the reaction jet nozzles located on the outer trailing edges of the propeller blades.

20 In an airplane having means for propelling the same either by employing reaction jets or by rotating propellers, it is desirable that the construction be such that the change from one means of propulsion to the other may be accomplished by either, and the pitch of the propeller blades be controllable when being propelled by rotating propellers to maintain the rotation of the propellers at a constant speed by changing the pitch of the propeller blades as the density of the atmosphere may vary by reason of a change in altitude of the aircraft in flight to provide the most efficient pitch for the propeller blades consistent with the power being applied and the atmospheric density.

25 For instance, in ascending or descending under normal conditions, the change from propulsion by reaction jets to propulsion by rotating propellers, or vice versa, and the change of pitch of the blades of the propeller during such time that they supply the propelling means is desirable to be accomplished at the will of the pilot, and preferably by automatically operated mechanism.

30 In the present invention the change is made by merely changing the pitch of the blades. Means are provided for changing and for also reversing

the pitch of the blades, and there are times when it is highly desirable that this change pitch mechanism be manually controlled, as, for instance, in dive bombing. When nearing the limit of a dive under bombing conditions the pitch of the blades may be manually controlled to cause them to function as brakes for a brief period of time in order to relieve strains on the dirigible mechanism of the plane. In reversing the pitch of the blades for braking action to retard forward movement of the aircraft, there is a reversal in the direction of the air-screw effect but the propeller continues to rotate in the same direction.

The mechanism for varying the pitch of the propeller blades comprises a hollow cylindrical shaft 223, concentrically mounted within the propeller shaft 213, and is relatively rotatable therein, as by means of the anti-friction bearings 225^a and 225^b. Mounted on the outer end of the shaft 223 is the bevel gear 227 that engages bevel gears 226 and 226^a on the inner ends of the propeller blades for rotating the blades, as described above. The hollow shaft 223 has a spiral thread or gear 223^a thereon, which is engaged by an internal spiral groove in a sleeve 223^b. The sleeve 223^b is slidably mounted within the propeller shaft 213. An outer sleeve 229^a is slidably mounted on the drive shaft 213. These two sleeves are connected to slide together along the drive shaft, but are prevented from turning on said shaft by a plurality of blocks 220^b, which are slidably mounted in slots 220^c in the wall of the propeller shaft 213. Screws 220^d hold the sleeves and blocks together so that they may slide as a unit longitudinally of the shaft 223.

The means for moving the threaded sleeve and associated parts along the shaft 223 comprises a yoke or depending arms 220^e, pivotally mounted, as at 220^f, and having their lower ends at opposite sides of the hollow shaft bifurcated, as at 220^g, engaging blocks 220^h pivoted to an outer ring member 220ⁱ at opposite sides thereof, and which in turn surrounds the sleeve 220^a. Anti-friction bearings 220^j are provided between the ring 220ⁱ and the sleeve 220^a, and thus the sleeve 220^a, propeller shaft 213, and hollow shaft 223 normally turn together, while the ring 220ⁱ remains stationary so long as the arms 220^e remain stationary.

It will thus be seen that when the arms 220^e are turned about the pivot 220^f the ring 220ⁱ is moved along the propeller shaft, and due to the ball bearing connection and construction the sleeve 220^a, and with it the sleeve 223^b, are moved along the hollow shaft 223, thus rotating the latter for rotating the gear 227, which in turn rotates the gears 226 and 226^a for varying the pitch of the propeller blades.

The means for automatically and for manually rotating the arm 220^e will now be described.

The arm 220^e is extended beyond its pivot 220^f, and is provided with a toothed quadrant 220^k, which is adapted to be engaged by a self-locking worm 220^l on the shaft of a reversible motor 220^m, adapted to oscillate the arm 220^e in either direction. The operation of the motor is controlled by an automatic switch mechanism 1, or by a manually operated switch mechanism 2 (Fig. 1). The automatic switch mechanism 1 comprises a housing 2^x, which is rigidly connected to the housing 212 and has rotatably mounted therein a gear 3 which meshes with a gear 4 rigidly mounted on the propeller shaft 213. The gear 3 is rigidly mounted on a shaft 5, and a governor 6 is also mounted on this shaft 5.

Automatic governor for pitch control

The governor 6, which is of the usual centrifugal type, comprises a collar 7, rigidly connected to the shaft 5 and rotatable therewith. This collar has connected thereto the usual centrifugal ball and link connection 8, which is connected to a sleeve 9 slidable along the shaft 5. A spring 1^a is mounted on the shaft 5 between the collar 7 and sleeve 9 for normally holding the latter in its outermost position. Connected to the sleeve 9, as by means of a ball bearing 2^a, is a switch operating shaft 3^a, having rack teeth 4^a thereon. The shaft 3^a is free to move horizontally through a cylindrical casing 2^y, which is slidably supported at its inner end 2^m in a bearing support 2^k rigidly attached to the open end of the housing 2^x. The bearing support 2^k has an extension 2^s, to which are attached the two fixed elements 4^m and 4^b of a multiple switch 6^a.

The casing 2^y has extensions 2^l, to which is attached the movable element 5^a of a multiple switch 6^a extending outwardly through the slot 2ⁿ in the extension 2^s of the bearing support 2^k, and is yieldingly held in adjusted position by a spiral toothed gear 2^p, rotatably mounted in a spring-pressed block 2° slidably mounted in a bore 2^r in the lateral extension 2^t of the casing 2^y. The spring compression is controlled by the threaded bolt 2^w. The gear 2^p, meshing with the rack teeth 4^a, holds the casing 2^y in adjusted position without offering too much frictional resistance to the endwise movement of the shaft 3^a.

The switch operating shaft 3^a does not rotate but is adapted to be moved longitudinally of the shaft 5 by the centrifugal governor mechanism 6. Likewise the casing 2^y, which is slidably mounted on the shaft 3^a, does not rotate but is adapted to be moved in either direction by the frictional contact between the spiral toothed gear 2^p and the rack teeth 4^a by a corresponding movement of the shaft 3^a until the movable element 5^a contacts either of the fixed elements 4^m or 4^b of the multiple switch 6^a. After such contact the sleeve 2^y is prevented from moving further in that direction, but the shaft 3^a may continue to move in the same direction if the speed of the governor continues to increase or decrease, as the case may be.

The movable element 5^a of the switch 6^a is provided with a pair of contact members 7^a and 8^a. The contact member 3^a, when at one extreme position, is adapted to engage a pair of contact members 1^b, 2^b, and the contact member 7^a is adapted to engage the contact member 3^b on the fixed portion 4^b of the switch 6^a. When moved in the opposite direction the terminal 8^a is adapted to engage the two terminals 5^b, 6^b, of the fixed portion of the switch, and the terminal 7^a will contact the terminal 7^b of the fixed portion of the switch and make electrical connections therewith.

Electric circuits for change pitch mechanism

When the plane passes from one density of the atmosphere to another, as when ascending, it passes into rare atmosphere, the propeller, having less resistance due to the rarity of the atmosphere, will tend to move faster, and this will cause the balls of the governor 6 to move out by centrifugal force, causing the sleeve 9 to move to the left in Fig. 1, and this in turn will move the sleeve 3^a, and with it the movable element 5^a of the switch, thereby bringing the terminals 7^a, 8^a, in contact 75 with the terminals 7^b, and 5^b, 6^b, respectively.

When these connections are made the electric current from a suitable source of electrical energy, as the battery 8^b, will cause the motor 220^m to rotate in one direction for increasing the pitch of the blades, as will presently be described.

In passing into a denser atmosphere the reverse will be true, and the electrical connections will be changed so that the motor will be rotated in the opposite direction for decreasing the pitch of the propeller blades. The motor employed is shunt wound, and the reversal of the motor is effected by reversing the field which is secured by reversing the flow of current through the shunt winding from the battery.

Assuming that the movable element 5^a of the switch 6^a has been moved to the left in Fig. 1 and made electrical connections with the terminals on the fixed portion of the switch, and assuming that the blade switch 9^b, which is connected to the terminals 4^c, 2^c and 3^c, is now in contact with the terminals 4^c, 5^c and 6^c, the current may be traced as follows:

From the battery 8^b through the switch 350 to the main line B, terminal 8^a, where it divides, one portion passes to terminal 6^b, through a conductor 3^e to the terminal 4^c across the switch to the terminal 1^c, and from the terminal 1^c through the conductor 7^c to the terminal 3^c of one of the brushes of the motor, and thence returning through the other brush and terminal 9^c of the motor, thence through the conductor 1^d, back through the main line A to the ground, as at 2^d.

The other portion of the current passes from the terminal 8^a to the terminal 5^b through a conductor to the terminals 6^c and 3^c of the switch 9^b through the conductor 3^d to the terminal 4^d of the field winding, thence through the field to the other field terminal 5^d, through conductor 6^d, terminal 2^c, switch 9^b, terminal 5^c, thence through terminals 7^b, 7^a, and finally through conductor 6^e and conduit A to the ground 2^d. The rotation of the motor causes the arms 220^e to rotate in one direction, which in turn moves the sleeve 223^b along the cylindrical shaft 223, thus rotating the cylindrical shaft 223 independently of the propeller shaft 213 for causing a change in the pitch of the propeller blades.

The motor 220^m continues to operate and move the sleeve 223^b, causing the pitch of the propeller blades to continuously increase until the added resistance to the rotation of the propeller causes it to decrease its speed. As the speed decreases the governor 6 acts to move the shaft 3^a to the right, carrying with it the casing 2^y and the attached movable element 5^a, breaking the electrical contact between its terminals 8^a and 7^a and the terminals 6^b, 5^b and 7^b, respectively, and stopping the motor 220^m and leaving the blades of the propeller locked in a fixed position, by the self-locking worm 220^l, with the toothed quadrant 220^k of the arms 220^e.

When the switch member 5^a is moved to the right in Fig. 1, as when the plane moves into denser air, and the speed of the propeller decreases due to this denser air, the contacts are made at the opposite side of the switch, thus reversing the current through the field and reversing the motor, which in turn lowers the pitch of the blades through the gears 226, 227 and 226^a. The circuit may now be traced as follows:

From the battery 8^b through the main line B to the switch terminal 8^a, terminal 1^b, conductor 1^c, terminal 5^c, through the blade of the switch 9^b to terminal 2^c, conductor 6^d to the terminal 5^d of the field 7^d, back through the terminal 4^d of

the field, conductor 3^d, terminal 3^c, blade of the switch 9^b to the terminal 6^c, thence through the conductor 2^e, terminal 3^b, terminal 7^a, conductor 6^g, through the main line A to the ground, thus reversing the motor.

The current through the brushes of the motor may be traced as follows:

From the battery 8^b through the switch 350 to main line B, to the terminal 8^a, through the terminal 2^b, conductor 3^e to the terminal 4^c, through the blade of the switch 9^b to the terminal 1^c, conductor 7^c, terminal 8^c of the motor to the terminal 9^c of the motor, conductor 1^d, and through the main line A to the ground.

Thus it will be seen that when the propellers are controlled to be operated at any rotational speed within its speed range by suitable manipulation of a control valve or element, the mechanism just described will act to automatically cause the pitch of the propeller blades to increase until the amount of power applied to the propeller is no longer able to increase its rotational speed against the increasing pitch of its blades, and will then act to lock the blades in a position of pitch most efficient for the maximum rotational speed of the propeller with the amount of power being applied.

Likewise, with the propellers operating as above described, the motor 220^m will be caused to rotate in such direction as to automatically increase the pitch of the blades should the aircraft ascend, or decrease the pitch of the blades as the aircraft descends, to maintain the rotational speed of the propeller at a constant through variation of the atmospheric density.

The main line B is in series with the switch 350 (Fig. 1), so that when the ignition circuit for the pressure generator 19 is open the circuit for the motor 220^m will likewise open, and the motor will not function.

It is significant that the automatic governor for propeller pitch control does not provide some specified pitch angle for a given number of R. P. M.'s of the propeller, but rather introduces another variable so that the governing means responds not only to changes in the power input to the propeller, but also the fluid resistance to rotation of the propeller to provide a pitch for the propeller which effectively absorbs the power being applied by said power means to rotate the propeller.

Manual control for changing pitch of propeller blades

When it is desired to vary the pitch of the propeller blades manually, the switch 9^b is moved over to the opposite side in contact with the terminals 4^c, 5^c and 6^c, so that the automatic operation of the switch mechanism for the motor 220^m is ineffective. The switch mechanism 2 can then be operated manually so as to vary the pitch of the propeller blades. The switch mechanism 2 comprises a casing 7^e, having a shaft 8^e extending therethrough, on which is slidably mounted a sleeve 9^e having gear teeth 1^f on one side thereof. A lever 2^f, pivoted in the casing, as at 3^f, and having gear teeth 4^f, is provided for shifting the sleeve. The sleeve is normally held in neutral or central position by springs 5^f and 6^f, which engage on opposite sides of the sleeve 9^e, as clearly shown in Fig. 5 of the drawing. Rigidly attached to the sleeve 9^e is the movable element 7^f of a switch, which is adapted to contact the stationary members 8^f, 9^f, at opposite sides of the movable element 7^f of the switch.

78

Since the switch 2 is constructed like the switch 4, it is not thought necessary to repeat the description. It is believed to be obvious how the circuits may be traced, since they are similar to those involving the switch 6^a, and consequently the tracing of the currents is not repeated.

It is thought from the foregoing, taken in connection with the accompanying drawings, that the construction and operation of my device will be apparent to those skilled in the art, and that changes in size, shape, proportion or detail may be made without departing from the spirit and scope of the appended claims.

I claim as my invention:

1. In an aircraft, a propeller having blades, reaction jets mounted on the propeller blades for normally rotating the propeller as a primary propulsion means for the aircraft, means to automatically vary the pitch of said blades to compensate for changes in air speed and barometric pressure, and means to reverse the pitch of the blades independently of said automatic means thereby to reverse the thrust of the propeller.

2. A propulsion device for use in fluid mediums, said device comprising a bladed variable pitch propeller, power means to rotate said propeller, a mechanism for altering the pitch of the propeller, and automatic means responsive to changes in the power input to said propeller and to the fluid resistance to rotation of said propeller for operating said mechanism to provide a pitch for the propeller which effectively absorbs and balances the power being applied by said power means to rotate said propeller, said automatic means comprising a first means that varies in accordance with the speed of the propeller, a second means operatively associated with said pitch altering mechanism and responsive to an initial variation in said first means for effecting a progressive change in pitch in said propeller in a direction that will oppose the change of speed causing variation in said first means, said second means including a third means providing a variable coupling between the first and second means for continuing said progressive change in pitch until final stabilization of the pitch and speed of the propeller has been established for the changed conditions under which the propeller is being rotated.

3. A propulsion device according to claim 2, in combination with means for selectively varying the pitch of the propeller by manual control.

4. A propulsion device according to claim 2, in combination with manual means for selectively varying the pitch of the propeller, means for reversing the pitch of said propeller whereby the propeller acts as a brake, and means to control the pitch of said propeller blades when in reverse pitch by said manual means.

5. A propulsion device for use in aircraft, said device comprising a bladed variable pitch propeller, power means to rotate said propeller, a self-adjusting governor mechanism responsive to the speed of rotation of said propeller as it may be affected by variations of power input, air speed, and barometric pressure to control and select the rotating speed and pitch of said propeller, said mechanism comprising a governor responsive to the rotation speed of the propeller, an arm operatively connected to said governor and having longitudinal movement in response to changes in the speed of rotation of the propeller, a contact member projecting from one side of said arm and movable with respect to said arm longitudinally, means associated with the arm

and contact member to present a resistance to movement of said member with respect to said arm, a pair of contacts positioned to either side of said member and spaced therefrom, electrically controlled means adapted to vary the pitch of the blades of said propeller, electric circuits connecting said last-mentioned means, said contact member, and said contacts whereby an increase in speed of rotation of said propeller will move said member against one of said contacts to complete a circuit through said last-mentioned means to increase the pitch of said propeller until the speed of rotation of the propeller becomes stabilized by the said increase in pitch, 15 while a decrease in the speed of rotation of said propeller will move said member against the other of said contacts to complete a circuit through the said last-mentioned means to decrease the pitch of the propeller blades until the 20 speed of rotation of the propeller becomes stabilized by the said decrease in pitch, whereby a proper rotating speed and blade pitch is automatically selected to absorb and balance any given power input applied to rotate the propeller and compensate for changes of air speed and 25 barometric pressure.

6. A propulsion device for use in fluid mediums, said device comprising a bladed variable-pitch propeller, power means to rotate the propeller, 30 pitch adjusting means for varying the pitch of the propeller, and a governing device automatically responsive to changes in speed of rotation of said propeller for operating said pitch adjusting means to effect a combination of pitch setting and speed of propeller rotation to effectively absorb and balance the power being applied by the power means to rotate the propeller, said governing device including a first part movable along a given path with its position on said path determined by the speed of rotation of the propeller, a second part slidably mounted with respect to said first part and movable therewith unless restrained from such movement, a third part adjacent said path and relatively fixed against movement, and a centering device including two spaced arms carried by one of said two last-named parts, and a third arm extending between said two spaced arms and carried by the other of said two last-named parts, and means operative to change the pitch of the propeller in one direction when said third arm makes contact with one of the two spaced arms, and to change the pitch of the propeller in the other direction when the third arm makes contact with the other of said two spaced arms, said second part being movable relative to the first part to a new position with respect thereto whenever the cooperating arms of the centering device make contact with a predetermined minimum pressure.

7. A propulsion device for use in fluid mediums, said device comprising a bladed variable-pitch propeller, power means to rotate the propeller, pitch adjusting means for varying the pitch of the propeller, and a governing device automatically responsive to changes in speed of rotation of said propeller for operating said pitch adjusting means to effect a combination of pitch setting and speed of propeller rotation to effectively absorb and balance the power being applied by the power means to rotate the propeller, said governing device including a first part movable along a given path with its position on said path determined by the speed of rotation of the propeller, a second part slidably mounted with

respect to said first part and normally movable therewith but capable of relative movement with respect to the first part, stabilizing means for shifting said second part with respect to said first part in response to excessive movement of said first part, said stabilizing means being operatively connected to said pitch-adjusting mechanism to effect a change in pitch in a direction that tends to resist the change in speed of rotation that caused the movement of the first part, whereby said second part establishes a new position with respect to the first part and the pitch and speed of the propeller are automatically adjusted to values that effectively absorb and balance the power input applied to the power means for rotating the propeller.
